COMBINATION HOOP AND JUMP DEVICE

Dwight C. Brown, 414 N. Granada St.,
Arlington, Va. 22203

Filed May 2, 1969, Ser. No. 16,992

Term of patent 14 years

Int. Cl. D21—03

U.S. Cl. D34—5

FIG. 1

FIG. 2

FIG. 3

FIG. 1 is a front view in elevation of the combination hoop and jump device of the present invention;

FIG. 2 is a side view in elevation of the combination hoop and jump device as seen from the right-hand side of FIG. 1; and

FIG. 3 is a top plan view of the combination hoop and jump device shown in FIG. 1.

I claim:

The ornamental design for a combination hoop and jump device, as shown.
